UNITED STATES PATENT OFFICE.

FRIEDRICH WILHELM STEINENBÖHMER, OF ISERLOHN, GERMANY.

CANDLE-HOLDER.

SPECIFICATION forming part of Letters Patent No. 611,397, dated September 27, 1898.

Application filed December 22, 1897. Serial No. 663,000. (No model.) Patented in Germany June 17, 1895, No. 92,649; in Austria December 16, 1895, No. 45/4,901, and July 12, 1897, No. 47/2,687; in Belgium January 24, 1896, No. 119,520, and November 18, 1896, No. 124,640; in France February 6, 1896, No. 253,748, and in England June 19, 1896, No. 13,585, and October 8, 1896, No. 22,320.

To all whom it may concern:

Be it known that I, FRIEDRICH WILHELM STEINENBÖHMER, a citizen of the German Empire, residing at Iserlohn, in the Province of Westphalia, Germany, have invented a new and useful Candle-Holder, (for which I have obtained patents in Austria, dated December 16, 1895, No. 45/4,901, and July 12, 1897, No. 47/2,687; in France, dated February 6, 1896, No. 253,748, and certificat d'addition November 19, 1896, No. 253,748; in Belgium, dated January 24, 1896, No. 119,520, and certificat d'addition November 18, 1896, No. 124,640; in England, dated June 19, 1896, No. 13,585, and October 8, 1896, No. 22,320, and in Germany, dated June 17, 1895, No. 92,649, published July 22, 1897,) of which the following is a specification.

This invention relates to candlesticks having the candle supported on a spring-pressed follower or bearer which is arranged within the candle-holding tube and forced upward by the action of the spring, so as to keep the wick always above the top of the candlestick as the candle burns away.

Heretofore in these devices the melted stearine, paraffin, or other material of the candle has often run down between the tube and the bearer. To guard against this, I make the upper end of the bearer and the lower part of the terminal cap of said tube correspondingly conoidal in form and provide the said cap with an inwardly-extending annular stop-flange in a horizontal plane above that of their line of contact, so that when there is only the base of the candle left it will still be held properly in position and the upward pressure of the spring will tighten the conoidal surfaces more and more together below it, making a joint through which the molten material of said tip will not flow downward. I also provide means for facilitating the inspection of the candle through the candlestick or holder and otherwise improving the device, substantially as hereinafter set forth and claimed.

My improvements are in part applicable to candle-lanterns as well.

Figure 1 is a longitudinal section through

the center of the candle-holder tube with a long piece of candle in it and with a top cap. Fig. 2 is a similar section showing only the upper part of the candle-holder with a piece of candle in it nearly burned up. Fig. 3 shows an outside view of a candle-holder like Fig. 1, with a foot connected thereto for use as a candlestick. Fig. 4 is partly a longitudinal section of a candlestick with a top cap hinged to the holder-tube and with knobs indicating the length of candle therein. Fig. 5 shows the top of Fig. 4 with the candle nearly burned up. Fig. 6 shows part of the outside of Fig. 4. Fig. 7 is a section through Fig. 6 along line I I. Fig. 8 is an outside view of my candle-holder, the top cap carrying a lantern-housing in closed state. Fig. 9 shows the same, the lantern-housing turned on one side. Fig. 10 shows the top part of my new candle-holder provided with a shade.

In all forms of execution the candle-holder consists of the combination of the following main parts: the candle-holding tube *a*, which is closed at one end and open at the other; the locking-cap *b*, with a conical or otherwise shaped inside, capable of forming a seat like a valve-seat; the candle-bearer *c*, fitting with its top into the cap *b*, like a valve in its seat, and forming there a closed joint, and the pressure-spring *d*, which pushes the candle-bearer, with the candle on it, upward against the inwardly-turned small flange *e* of the locking-cap, so that the candle will always be pushed upward as it is reduced by burning, but that it cannot be thrown out upward by the pressure of the spring *d*. These parts form the foundation of my invention. In their design and working they may vary, and do vary, in minor details, in order to produce the candle-holder at a lower or higher price and to be able to combine it with other parts, according to the special use for which the candle-holder is intended. Such other parts of secondary importance may be added thereto to make the candle-holder fit to answer the objects named above.

The main object in all cases is to form a closed valve-like joint between the locking-cap and the candle-bearer, so that when the

candle is burned down nearly to the end and the candle-bearer is pressed into the locking-cap no fluid candle matter shall be able to run into the interior of the tube.

5 In Figs. 1, 2, and 3 the locking-cap *b* is connected to the upper part of the candle-tube *a* by means of an ordinary bayonet-joint. This is the simplest form of execution. When a new candle has to be introduced, the cap *b* 10 is put on its top, the small flange *e* pressing against or resting upon the reduced edge of the candle-top. The candle-bearer *c* then being about in the position shown in Fig. 2, the foot of the candle is put thereon, and then it 15 is pressed downward into the tube, the spring *d* being compressed until the cap has reached the position indicated in Fig. 1. The cap is then fully pressed down and turned a little, so that the vertical recess in the corner of the 20 horizontal side of the slot stands just over the knob *g*, when it is allowed to go back a little and lock itself fast.

This candle-holder may be provided at the bottom with a dish-shaped foot *h*, as shown 25 in Fig. 3 and also in Fig. 4, to make an ordinary candlestick. It may also be provided about in the middle of its length with a male screw-thread, as shown at *i*, Fig. 1, so that a lantern-housing *k* can be screwed thereon, as 30 shown in Fig. 8 and as I will explain more fully hereinafter.

When arranged as a candlestick, it may be desirable to have some means allowing to 35 see how much candle there is left unburned, and for this purpose small holes or perforations *m'*, as shown in Fig. 3, are made in the tube *a*, or two radially-opposite longitudinal slots *m*, as indicated in Figs. 4 to 7, are cut into the candle-tube *a'*. In the latter case a 40 diametrical pin *n* is put through the slots, going also through the lower part of the candle-bearer *c*, which is bored accordingly, and through the spirals of the spring *d* knobs *o* are fixed to the projecting ends of the pin *n* 45 to secure it at both sides against falling or being pulled out. From Figs. 4 and 5 it will now be easily understood that these knobs and the pin not only are convenient means for the indication of the length of unburned 50 candle in the candlestick, but that they are also a very practical device for compressing the spring *d* when a new candle is to be introduced, so that this needs no further to be pressed down by the cap. In order to make 55 this still more convenient, the slots *m* at the bottom end in horizontal recesses *p*, Figs. 6 and 9, and into these recesses the pin *n* is turned when arrived at the bottom. It is then locked fast, so that now the candle can be conveniently inserted. Now in combination with 60 this arrangement I prefer instead of the bayonet-joint cap *b* a hinged locking-cap *q*, as one is shown in Figs. 4 and 5. Here the conical socket of this cap is provided with a flange *r*, and a corresponding flange *s* is arranged at 65 the top of the tube *a'*, both flanges being joined together by a hinge *t*, so that the flange

r, with the socket, can be turned on one side, as indicated in dotted lines in Fig. 4. A swivel *u* on the flange *r* and passing through a slot *u'* in the flange *s* serves to lock both flanges together, so that the upper flange and socket cannot be turned open by the pressure of the candle and spring. This arrangement has the advantage that even if the 75 swivel should happen to stand in opening position, so that it can pass through the slot in flange *s*, the cap cannot be opened and the candle thrown out accidentally, because the candle, reaching into the socket and being 80 jammed therein firmly, would hinder the turning of the same, because it would be placed edgewise.

As shown in Figs. 2 and 5, when only the 85 last fragment of the candle remains unburned it will be held in position at the top of the candlestick below the flange *e*, with the wick and flame above the latter. The spring *d* forces the conoidal face of the upper end of the follower or bearer *c* against the corresponding conoidal inner face of the cap *b* at a point below the said flange and holds it so tightly that the material melting from this fragment of the candle will be sealed against running down within the tube. The upper 95 part of the interior of the cap thus practically forms an inclosure with a closed bottom containing the still unmelted fragment of the candle.

I have already pointed out above that my 10 candle-holder very conveniently can be arranged for use as a lantern. This variation is shown in Figs. 8 and 9. In Fig. 8 the tube *a* of Fig. 1, with the screw-thread *i* on it, is used. A socket *v*, having female thread at its lower 10 end and fitting upon the thread *i*, is screwed thereon. At its crown this socket carries a suitable lantern-housing *k* with glass windows and a door *w*. It needs no special mention that the housing may be fitted in any 11 other suitable manner with the candle-holder, and I do not limit myself to the special manner of connection shown.

The example shown in Fig. 10 differs from the preceding lantern only in this, that here 11 the candle-holder of Fig. 4 is used with the hinged top cap. The flanges *r'* and *s'* in this case of course have got such shape as to correspond to the shape of the bottom of a lantern-housing, which in this case, as shown by 12 the drawings, can be turned on one side when a new candle has to be introduced. By means of an arm *l* this lantern can be fixed to a bracket, as indicated in dotted lines. Finally, I have shown in Fig. 10 the tube part of my 12¹ new candle-holder with a hinged locking-cap when the flange *r*² is provided with a socket *x*, into which is stuck a small post *y*, carrying at its top a shade-holder or reflector *z*. This shade-holder, as will be seen from the 13⁰ drawings, can be conveniently removed, if desired. A similar arrangement of course might be added to the candlestick shown in Fig. 3. All that would have to be done is to

provide a suitable support for the shade-holder or reflector. The candlestick shown in Fig. 3 may also be provided with a disk r^3 , as shown in dotted lines, to which a shade-holder may be fixed in a similar manner. This disk at the same time prevents fluid candle-matter dropping down at the sides.

I am aware that prior to my invention candlesticks have been known in which the candles are pressed upward by a spring, and I do not claim this combination, broadly; but

What I do claim as my invention, and desire to secure by Letters Patent, is—

1. In a candlestick, the combination of a candle-holding tube provided at its upper end with a conoidal cap having an inwardly-projecting flange at its upper edge, in combination with a conoidal candle bearer or follower, adapted to fit against the inner face of the said cap at a point below the said flange, and a spring which forces the said bearer upward to tighten the joint between the said conoidal faces and prevent the downward leakage of the material melted from the base or last piece of the candle when the rest of it is consumed, while allowing the said piece to be held in place against the flange substantially as set forth.

2. In a candle-holder in combination with a tube a' closed at one end and having longitudinal slots m at its sides, a flange s at the top of said tube a' , a slot u' in said flange, a cap b' having an inwardly-directed small

flange e at the upper edge and a flange r at the lower edge corresponding with said flange s and connected to it by a hinge t , a swivel u on said flange r for holding both flanges together, a candle-bearer c corresponding in shape to the inner side of the cap b' and bored through horizontally, a pin n passing through the slots m and the boring in the candle-bearer; knobs o at the ends of the pin, a spiral spring d resting on the closed end of the tube a' and pressing said candle-bearer with its upper end into or against the seat in the cap b' and a dish-shaped foot h to which the tube a' is fixed at its bottom, the whole as illustrated and described and for the purpose set forth.

3. In a candle-holder in combination with a tube a' closed at one end and having longitudinal slots m at its sides, a flange s' at the top of said tube a' , a slot in said flange, a cap b' having an inwardly-directed small flange e at the upper edge and a flange r' at the lower edge corresponding with said flange s' and forming the bottom of a lantern-housing k' fixed on top of said flange r' , said lantern-housing being hinged to the flange s' , a swivel serving to lock both flanges r' and s' together, the whole as illustrated and for the purpose set forth.

FRIEDRICH WILHELM STEINENBÖHMER.
